UNITED STATES PATENT OFFICE.

HENRY LEWIS GUY, OF MANCHESTER, ENGLAND, ASSIGNOR TO THE BRITISH WESTINGHOUSE ELECTRIC AND MANUFACTURING COMPANY, A COMPANY OF GREAT BRITAIN.

STEAM-TURBINE.

1,379,258.

Specification of Letters Patent. Patented May 24, 1921.

Application filed November 16, 1918. Serial No. 262,877.

To all whom it may concern:

Be it known that I, HENRY LEWIS GUY, a subject of the King of Great Britain, and a resident of Manchester, in the county of 5 Lancaster, England, have invented a new and useful Improvement in Steam-Turbines, of which the following is a specification.

This invention relates to removable nozzle boxes for steam turbines and more particularly to nozzle boxes of the kind described 10 in United States Patents, Nos. 1,286,204, filed Jan. 31, 1917, and 1,325,135, filed Feb. 18, 1918, and application for United States patent, Serial No. 217,947, filed Feb. 18, 1918.

15 The nozzle boxes described in said specifications take the form of elongated hollow chambers adapted to be located within and attached to the cylinder or a part secured thereto. In order that the relative position 20 of the nozzles of the nozzle box with respect to the moving blades of the turbine with which they cooperate may be maintained substantially constant notwithstanding movements of the nozzle box due to expansion, 25 guiding means are provided which permit movement of the box to take place only in a plane perpendicular to the turbine axis.

The present invention has for its object 30 to provide a nozzle box of the aforementioned kind so constructed that means for guiding movement of the nozzle box, due to expansion, may if desired be dispensed with. This is accomplished, according to the present invention, by providing the nozzle 35 box with a stiffening rib or ribs or by increasing the thickness of its walls at parts so located that the box when in position within the turbine will have greater flexibility in a plane perpendicular to the turbine 40 axis than in a plane parallel thereto. In this way movement of the nozzle box due to expansion will take place more readily in a plane perpendicular to the turbine shaft and movement of the box and consequently 45 of the nozzles toward or away from the moving blades will be substantially eliminated.

The invention is illustrated in the accompanying drawing in which Figure 1 is a partly sectional view of the high pressure 50 end of a steam turbine having nozzle boxes located therein constructed in accordance with the invention and Figs. 2-5, inclusive, are detail views thereof more particularly hereinafter explained, Figs. 2 and 3 being

taken along the lines 2-2 and 3-3, respectively, of Fig. 1.

In the drawing the turbine cylinder is indicated at 6 in the upper half of which is located a nozzle box 7 of the kind described in the specifications of the aforementioned 60 patent applications, and specifically illustrated in United States patent application, Serial No. 217,948. The nozzle box is provided with a longitudinal rib 8, see Fig. 2, having the effect of stiffening the box in a 65 direction parallel with the turbine axis and causing movement of the same, due to expansion, to take place in a plane perpendicular to said axis, the position which the box will assume when expanded being indicated in dotted lines.

The nozzle box 9 located in the lower half of the cylinder has its outer wall, *i. e.*, the wall opposite the nozzle openings 10 increased in thickness as shown in Fig. 3, 75 which will cause movements of the box, due to expansion, to take place in a plane perpendicular to the turbine axis as indicated by the dotted lines.

With nozzle boxes constructed as described 80 above, although guiding means of the kind hereinbefore referred to may be dispensed with, it may in some cases be found desirable to provide suitable restraining means for preventing movement of the nozzle box in 85 the axial direction of the turbine. Two forms which may conveniently be adopted are illustrated in Figs. 1, 4 and 5 of the drawing and comprise one or more lugs or 90 projections 11 on the turbine cylinder, another lug or projection 12 on the nozzle box, and a pin 13 passing through said lugs. The position of the pin 13 is such that movement 95 of the box, due to expansion, will be a rotary one around said pin. It will thus be seen that the restraining means takes the form of a hinge between the turbine cylinder and the nozzle box.

Although the invention is illustrated herein as applied to the forms of nozzle box 100 more particularly described in the specification of patent application Serial No. 217,948, it is to be understood that it is not limited in its application to these particular forms of nozzle box as it may equally well 105 be applied to any form of nozzle box constructed in accordance with any of the patent applications hereinbefore recited.

I claim as my invention:—

1. In combination in a steam turbine, a removable nozzle box stiffened longitudinally thereof, the stiffened portion being so located with relation to the box that the box when in position within the turbine will have greater flexibility in a plane perpendicular to the turbine axis than in a plane parallel thereto.
- 10 2. In combination in a steam turbine, a nozzle box so supported from the turbine case that it is free to expand and contract substantially independently of the case, and stiffened longitudinally thereof so that the 15 box will have greater flexibility in a plane perpendicular to the turbine axis than in a plane parallel thereto when the box is in place within turbine case.
- 20 3. In combination in a steam turbine, a nozzle box so supported from the turbine case that it is substantially free to expand or contract independently of the case and so stiffened as to resist deflection in planes other than in a plane at right angles to the 25 axis of the turbine.
- 30 4. A nozzle block as set forth in claim 3 provided with restraining means for preventing movement thereof in the axial direction with relation to the case comprising a pivotal connection at or near the outer end thereof, the axial position of which is such that the movement of the box due to expansion or contraction will be a rotary one around the axis of said connection, substantially as described.
- 35 5. In combination in a steam turbine, an elongated nozzle box supported on the turbine case at a point intermediate the ends of the box and stiffened longitudinally, so that 40 the box will have greater flexibility in a

plane perpendicular to the turbine axis than in a plane parallel thereto when the box is in place in the turbine case.

6. A nozzle box as set forth in claim 5 provided with restraining means for preventing movement thereof in an axial plane with relation to the case, comprising a pivotal connection near an outer end of the box, the axial position of which is such, that the movement of the box due to expansion or 45 contraction will be a rotary one around said pivotal connection, substantially as described.

7. In combination with a turbine, a nozzle box secured to the turbine case so that an 55 end thereof is substantially free to expand independently of the case, and a stiffening rib extending longitudinally of said free end and so located with relation to the box that the free end thereof will have greater flexibility in a plane perpendicular to the turbine axis than in a plane parallel thereto, when the box is in place on the turbine case.

8. In combination with a turbine, a removable nozzle box having a longitudinally 60 extending stiffening rib and rigidly secured to the case at a point intermediate the ends of the box, said stiffening rib being so located that the box when in place in the turbine will have greater flexibility in a plane 65 perpendicular to the turbine axis than in a plane parallel thereto.

9. A nozzle box as set forth in claim 8 in which a pivotal connection is provided between one end of the box and the case substantially as and for the purpose described.

In testimony whereof I have hereunto subscribed my name this fourteenth day of October, 1918.

HENRY LEWIS GUY.
